UNITED STATES PATENT OFFICE.

DAN K. NEWMAYER, OF HOUSTON, TEXAS.

SPIRIT LEVEL.

Application filed June 1, 1925. Serial No. 34,245.

My invention relates to an improvement in spirit levels, and is particularly applicable to spirit levels employed in track work on railways.

5 Levels employed on railway work for leveling up the rails are subjected to rather hard usage with the result that they easily become broken and out of repair, and it is also an objection that the level must be long 10 enough to reach from one rail to the other, and in levels of this length, the device easily becomes warped and bent.

It is an object of my invention to provide 15 a level for track work wherein the spirit level is so mounted that it will not easily be broken or injured by the warping or bending of the body of the level. It is also desired to protect the device from breaking under shocks or blows, and to maintain the 20 device in alignment under all circumstances.

Referring to the drawing herewith, Fig. 1 is a top plan view of a structure embodying my invention. Fig. 2 is a side view, partly in elevation and partly in vertical 25 section. Fig. 3 is an end elevation thereof. Fig. 4 is also an end elevation taken from the end opposite to the view shown in Fig. 3; and Fig. 5 is a vertical section on the line 5—5 of Fig. 2.

30 In order that the device may be easily portable, the body 1 of the level is preferably made of wood, or some other light rigid material. In the embodiment shown in the drawing, I have divided the body into two sections, hinged on the lower side, as shown at 2, and held in extended position by means of a latch 3 on the side thereof. The body of the level is provided with a longitudinal 35 groove, or channel, 4 extending the full length of the device and being of such depth as to include somewhat over one-half the thickness of a body of the level. At one end of the body of the level I employ a metal plate 5 which is bent at an angle on its lower 40 end to form a shield 6 covering the lower end of the body. At the end of the body of the level, the plate 5 extends upwardly to the full thickness of the device. As shown in Fig. 3, this plate is formed with a notch, or recess, 7 thereon to correspond with the channel 4 in the body of the level. The plate forms a bearing for a cross pin 8 extending transversely of the recess 7 at a point spaced somewhat upwardly from the lower wall of 45 the channel.

The opposite end of the structure has

thereon a similar plate 9 with a lower angular portion 10 thereon, and an upwardly extending end portion, which has a central aperture 11 therein to allow the attachment 60 of the level support. A transverse rod 12 extending across said aperture is curved inwardly to provide a short loop 13 for the attachment of a spring 14.

The spirit level, shown at 15, is mounted 65 upon a plate 16 in any desired manner, either by riveting or brazing, or other similar means. The end of the plate adjacent the rod 8 is curved about the rod to form a hinge 17 so that it may swing thereon. The end 70 of the plate 16, away from the hinge thus provided, is attached to a wire 18 which extends longitudinally of the channel 4 and is secured at its other end to the spring 14. The wire 18 and the spring 14 are of strong 75 construction, and I contemplate piano wire or other similar substantial construction. The spring 14 serves to maintain the wire 18 taut at all times so that the plate 16, upon which the spirit level is mounted, will be 80 always in alignment.

It will be noted that the hinge 17 and the rod 12 at the opposite end are secured to metal plates at points spaced equally above the lower side of the body 1 of the level; 85 hence when the device is placed upon the rails 19, the points of attachment for the ends of the wire 18 and plate 16 will be always spaced at equal points above the rail. If the wire and plate are then retained in 90 taut position by means of the spring, the level cannot easily get out of alignment and fail to perform its function properly.

The advantages lie in the fact that the 95 construction is light and durable, and the mounting of the level is such that it will withstand ordinary rough usage and be always maintained in accurate alignment. It is also to be noted that the device is easily portable in that the latch 3 may be disengaged and the spring 14 released from the rod 12, and the device may be then folded together in such manner that it will not take up excessive space longitudinally of the carrying receptacle. The further objects and 100 advantages of my invention will be obvious to those skilled in the art.

What I claim as new and desire to protect by Letters Patent is:

1. In a device of the character described, 110 a rigid body having a central channel longitudinally thereof, plates on said body at

each end thereof, a resilient line in said channel secured at each end of said body to said end plates, and a spirit level secured rigidly upon said line for the purpose described.

2. In a device of the character described, a longitudinal body of rigid material, said body being in two sections hinged together, end plates on said body, a supporting plate hinged to one of said end plates, a spring secured to the opposite end plate, and a wire connecting said supporting plate and said spring.

3. In a device of the character described, a rigid body having a longitudinal channel in the upper side thereof, end plates on said body, a line secured to said end plates at

equal distances from the lower side of said body, a spirit level on said line and means in said line to maintain the same in resilient alignment.

4. In a device of the character described, a rigid supporting body, a wire extending longitudinally therethrough, a supporting plate at one end of said wire, a spirit level on said supporting plate, a spring at the opposite end of said wire, and means for connecting said spring and supporting plate to the ends of said body at points spaced equally from the lower side thereof.

In testimony whereof I hereunto affix my signature this 29th day of May A. D. 1925.

DAN K. NEWMAYER.
